STEAM GENERATING PLANT

Johan Viktor Blomquist, Stockholm, Sweden,
assignor to Aktiebolaget Atmos, Stockholm,
Sweden, a corporation of Sweden

Application October 16, 1934, Serial No. 748,525
In Germany October 17, 1933

12 Claims. (Cl. 122—11)

My present invention relates to a steam generating plant comprising a rotatable steam generator assembled by a plurality of substantially straight steam generating tubes arranged around 5 a common axis so as to confine a combustion chamber, and in addition thereto super-heating and pre-heating surfaces. The main object of my invention is to construct and assemble the elements included in the plant so as to obtain a 10 simple construction requiring little space and, furthermore, having the advantage of enabling the dimensions of the masonry to be reduced to a minimum.

According to my present invention this is obtained by dividing the supply passages for the air 15 of combustion in such a manner that a portion of the air enters through the circumference of a part of the rotor formed by the generating-tubes and containing the combustion chamber, and a 20 portion together with the fuel through the end of the rotor, the outlet for the combustion gases being disposed at the bottom of the rotor so that the combustion gases escape downwards from the interior of the rotor through another portion 25 of the circumference. Thus, the firing takes place within the rotor formed by the steam-generating tubes, the gases produced at the combustion escaping downwards from the rotor. Rotatable steam generators have been previously 30 proposed in which the firing takes place within the rotor. Such a steam generator is disclosed by the Swedish patent specification No. 72,605. According to said patent specification, the combustion air flows into the rotor on a portion of 35 the circumference of the combustion chamber through the layer of fuel, and the combustion gases escape through the remaining portion of the circumference. But according to my present invention the combustion gases escape only on a 40 portion of the free circumference and then flow directly downwards passing to and over the heat absorbing surfaces disposed under the rotor to the chimney.

In order that my invention may be clearly 45 understood and readily carried into effect it will be described in the following, reference being had to the accompanying drawings, wherein

Figure 1 shows a longitudinal section of a steam generating plant according to the invention,

50 Figure 2 is a cross section of the same, and

Figure 3 is a cross section of three steam generating tubes together with grate bars and strengthening pieces provided therebetween.

The feed water is pumped through the water 55 heaters 1 and 2 into the container 3 as indicated

by the arrows, and is distributed by the tubes 4, the torus 5 and the tubes 6 to the steam generating tubes 7. At the other ends the tubes 7 are connected to the container 9. The tubes 8 open approximately at the centre of the tubes 7 in a 5 well-known manner so that the latter are always half filled with water. The container 9 is also half filled with water, and the water level is always maintained by an automatic feed water regulator in well known manner. The steam 10 generated in the tubes 7 will thus circulate through the tubes 8 into the container 9 and to the superheater 10 from which it is led to the place of consumption.

When the fuel consists of coals in the form of 15 pieces, it is supplied by a drum 11 and falls through an aperture 12 on a plate 13 by means of which the pieces of coals are deflected and guided to the space between the tubes 4 and into the combustion chamber 14. The plate 13 is 20 preferably disposed above the axis of the rotor so that the coals are passed eccentrically through the end of the rotor at a point near the top of the combustion chamber. A portion of the combustion air is supplied to the combustion chamber 25 under the plate 13 and laterally thereto, said air carrying away the coals which are stopped by the tubes 4. Due to the movement of the rotor the coals are distributed in a uniform layer 15 along the entire rotor.

The air of combustion heated in the two air 30 preheaters 16 and 17 flows substantially through the layer of coals 15 into the combustion chamber 14. The two spaces 18 and 19 above the air preheaters 16 and 17 are connected with each 35 other by a passage 20 from which another passage 21 deflects a portion of the air of combustion to the plate 13 as stated above.

To prevent leakage of air from the space 18 to the chimney flue 22 the air is not blown directly 40 from the air preheater 16 into the space 18 but may previously flow into the passage 23 which is provided with a restricted aperture 24 through which the air flows into the space 18 at a high rate. The jet formed by the air and directed 45 obliquely towards the steam generating tubes prevents leakage between the two spaces 18 and 22.

The gases produced in the combustion chamber 14 escape at a portion of the circumference 50 of the rotor through grate bars between the steam generating tubes to the chimney flue 22, flowing therefrom in the direction indicated by the arrows over the superheater 10 and the economizer 2. From this place they are guided to both sides 55

and then flow over the two economizers 1 through the two air preheaters 16 and 17 to the chimney flues 26 and 27 which are connected to the suction side of a ventilator supplying the smoke gases 5 to the chimney.

The combustion takes place when the fuel is floating. A rotor designed for a steam generation of for instance 40,000 kg/h at a pressure of 1422 lbs/inch² has a diameter of 158" and an effective length of 236", and rotates with a speed of 15 revolutions per minute. The coals are therefore moved to the top of the layer of coal in one second. When the layer of coal is very thin, the coals are blown by the air of combustion into 15 the combustion chamber 14 without slipping downwards on the layer of coal but falling directly on the steam generating tubes to be returned upwards successively. At the places where the layer of coal is thick the coals slip 20 rapidly down on the bed of coal, and during this interval no cakes of slag have time to be formed. When the coals have fallen on the tubes, they will be returned upwards and blown into the combustion chamber. Each particle of coal will 25 thus substantially be burned in a floating state until only ashes and slag remain, which is transferred together with a quantity of unburned coals by the gases of combustion over the superheater 10 and the economizer 2 to the ash-pit therebelow 30 cleansing continuously the heating surfaces from flying ashes due to the friction.

The higher the steam pressure and the greater the quantities of generated steam, the greater are the two containers 3 and 9 as well as their 35 wall thickness. The containers adapted for the above-mentioned steam generator designed a steam production of 40,000 kg/h should have a wall thickness of about 3.9" to resist said pressure without exceeding the safe stress. With such 40 wall thickness, however, the additional stresses due to the heating become too large in case the containers are exposed to the direct heat radiation.

Figure 3 shows a constructional form of the 45 gate bars 28 which are divided radially so that they may be inserted between the steam-generating tubes. Spaced apart are two special strengthening pieces 29 disposed between the 50 grate bars to give the construction sufficient strength. The grate bars are cooled sufficiently by the contact with the steam generating tubes and by the air of combustion.

The masonry is limited as shown to very small 55 dimensions. It is not exposed to the hottest gases of combustion, and since it is additionally cooled by the heating surfaces surrounding the combustion chamber, no damage due to combustion is to be feared. Furthermore, the rotor is enclosed by common insulating material externally 60 surrounded by a plate cover.

The generator may be arranged adjacent to a turbine in the machine house, the steam tubes having a minimum of length and small diameter.

Any combustible material may be used as fuel, 65 the supply of the material being modified correspondingly.

What I claim and desire to secure by Letters Patent is:—

1. In a steam generating plant, the combination comprising a rotatable steam generator rotor having a plurality of substantially straight steam generating tubes arranged around a common axis so as to define a combustion chamber, 70 means for passing a portion of combustion supporting air to the combustion chamber, through

a part of the circumference of the rotor formed by the steam generating tubes, means for supplying another portion of the air together with the fuel through the ends of the rotor, and an outlet for the combustion gases disposed at the 5 bottom of the rotor whereby the combustion gases escape downwards from the interior of the rotor through another part of its circumference.

2. In a steam generating plant, the combination comprising a rotatable steam generator rotor having a plurality of substantially straight steam generating tubes arranged around a common axis so as to define a combustion chamber, a restricted aperture for passing a portion of 10 the air of combustion tangentially to the steam generating tubes and into the combustion chamber through the circumference of the rotor formed by the steam generating tubes, air supplying means for supplying another portion of 15 the air together with the fuel through the end of the rotor, and an outlet for the combustion gases disposed at the bottom of the rotor, whereby the combustion gases escape downwards from the interior of the rotor through another part of 20 25 the circumference.

3. In a steam generator of the character described, a squirrel-cage shaped rotatably mounted boiler structure consisting of a plurality of substantially straight steam-generating tubes 30 concentrically grouped around the axis of rotation of said structure, and a series of tubular spokes positioned at each end of the boiler structure supporting the steam-generating tubes and communicating therewith, a hollow hub at one 35 end of the boiler structure, means for feeding water to said hub, said hub being adapted to form a communication means between said inlet and the tubular spokes at that end of the boiler, a second hollow hub at the opposite end 40 of the boiler structure, steam discharge means connected to said second hub, said last-mentioned hub being adapted to form a communication means between said steam-discharge means and the tubular spokes at the last-mentioned 45 boiler end, pivot and bearing means for supporting the whole boiler structure, and means for introducing fuel between the tubular spokes eccentrically in relation to the axis of rotation 50 of the boiler.

4. In a steam generator of the character described, a squirrel-cage shaped rotatably mounted boiler structure consisting of a plurality of substantially straight steam-generating tubes 55 concentrically grouped around the axis of rotation of said structure, and a series of tubular spokes positioned at each end of the boiler structure supporting the steam-generating tubes and communicating therewith, a hollow hub at one end of the boiler structure, means for feeding water to said hub, said hub being adapted to form a communication means between said inlet and the tubular spokes at that end of the boiler, a second hollow hub at the opposite end 60 of the boiler structure, steam discharge means connected to said second hub, said last-mentioned hub being adapted to form a communication means between said steam-discharge means and the tubular spokes at the last-mentioned boiler end, pivot and bearing means for supporting the whole boiler structure, and means mounted above the axis of rotation of the boiler structure for introducing fuel between the tubular spokes eccentrically relative to and above said axis of rotation.

5. In a steam generator of the character described, a squirrel-cage shaped rotatably mounted boiler structure consisting of a plurality of spaced steam-generating tubes grouped concentrically around the axis of rotation of said structure and connected by tubular spokes with hollow hubs at each end of the boiler structure, feed water inlet means communicating with one of said hubs, steam-discharge means connected with the other hub, pivot and bearing means for supporting the whole boiler structure, means for introducing fuel between the tubular spokes at one end of the boiler eccentrically relative to the axis of rotation of the same, and means for conveying the combustion gases from the squirrel-cage shaped boiler structure through the spaces between the steam-generating tubes thereof.

6. In a steam generator of the character described, a squirrel-cage shaped rotatably mounted boiler structure consisting of a plurality of spaced steam-generating tubes grouped concentrically around the axis of rotation of said structure and connected by tubular spokes with hollow hubs at each end of the boiler structure, feed water inlet means communicating with one of said hubs, steam-discharge means connected with the other hub, pivot and bearing means for supporting the whole boiler structure, means mounted above the axis of rotation of the boiler structure for introducing fuel between the tubular spokes eccentrically relative to and above said axis of rotation, and means for conveying the combustion gases from the squirrel-cage shaped boiler structure through the spaces between the steam-generating tubes thereof.

7. In a steam generator of the character described, a squirrel-cage shaped rotatably mounted boiler structure consisting of a plurality of spaced steam-generating tubes grouped concentrically around the axis of rotation of said structure and connected by tubular spokes with hollow hubs at each end of the boiler structure, feed water inlet means communicating with one of said hubs, steam-discharge means connected with the other hub, pivot and bearing means for supporting the whole boiler structure, means for introducing fuel between the tubular spokes at one end of the boiler eccentrically relative to the axis of rotation of the same, means for conveying the combustion gases from the squirrel-cage shaped boiler structure through the spaces between the steam-generating tubes thereof, and a steam superheater mounted in the path of travel of the combustion gases leaving the squirrel-cage shaped boiler structure.

8. In a steam generator of the character described, a squirrel-cage shaped rotatably mounted boiler structure consisting of a plurality of spaced steam-generating tubes grouped concentrically around the axis of rotation of said structure and connected by tubular spokes with hollow hubs at each end of the boiler structure, feed water inlet means communicating with one of said hubs, steam-discharge means connected with the other hub, pivot and bearing means for supporting the whole boiler structure, means for in-

troducing fuel between the tubular spokes at one end of the boiler eccentrically relative to the axis of rotation of the same, means for conveying the combustion gases from the squirrel-cage shaped boiler structure through the spaces between the steam-generating tubes thereof, and means for introducing a stream of air into the squirrel-cage boiler structure adjacent the fuel feeding means to facilitate the passage of fuel between the tubular spokes.

9. In a steam-generating plant, the combination of a rotatable steam generator rotor comprising spaced hub-like rotary headers axially aligned, a plurality of tubes projecting substantially radially from said hubs, and a plurality of steam generating tubes connecting the outer ends of the radial tubes on one hub with those on the other hub, a casing surrounding said generator and defining a combustion chamber within the space surrounded by said tubes, means for passing combustion supporting air through a portion of the circumference of said rotor, means for introducing air and fuel through one end of said rotor, and an outlet duct positioned beneath said rotor to cause combustion gases to pass downwardly from the interior of said rotor through another portion of the circumference thereof.

10. A rotating steam-generating boiler comprising a pair of axially spaced and aligned hub-like headers, means for rotatably mounting said headers, a plurality of tubes connecting said headers and arranged to define a cylindrical cage-like rotor, and means positioned above one of said hubs for feeding fuel eccentrically between the tubes defining one end wall of said rotor.

11. A rotating steam-generating boiler, comprising a pair of axially spaced and aligned spider-like headers, means for rotatably mounting said headers, a plurality of spaced tubes connecting said headers and arranged to define a cylindrical cage-like rotor the interior of which is adapted to form a combustion chamber, means for passing a portion of combustion supporting air to said combustion chamber through a part of the circumference of the rotor formed by the inter-space between the tubes, and means provided at one end of the rotor and adapted to introduce another portion of combustion supporting air together with fuel eccentrically relatively to the axis of rotation.

12. A rotating steam-generating boiler, comprising a pair of axially spaced and aligned spider-like headers, means for rotatably mounting said headers, a plurality of spaced tubes connecting said headers and arranged to define a cylindrical cage-like rotor the interior of which is adapted to form a combustion chamber, means for passing a portion of combustion supporting air to said combustion chamber through a part of the circumference of the rotor formed by the inter-space between the tubes, and means provided at one end of the rotor and adapted to introduce another portion of combustion supporting air together with fuel eccentrically relatively to the axis of rotation and at a zone above said axis.

JOHAN VIKTOR BLOMQUIST.
